US00D888821S

(12) **United States Design Patent** (10) **Patent No.:** **US D888,821 S**
Liao (45) **Date of Patent:** **** Jun. 30, 2020**

(54) **MICRO PRINTER**

(71) Applicant: **SHENZHEN WONUODE INTELLIGENT TECHNOLOGY CO., LTD.**, Shenzhen (CN)

(72) Inventor: **Weitao Liao**, Shenzhen (CN)

(73) Assignee: **SHENZHEN WONUODE INTELLIGENT TECHNOLOGY CO., LTD.**, Shenzhen (CN)

(**) Term: **15 Years**

(21) Appl. No.: **29/727,587**

(22) Filed: **Mar. 11, 2020**

(51) **LOC (12) Cl.** **19-02**

(52) **U.S. Cl.**

(57) **CLAIM**

The ornamental design for a micro printer, as shown and described.

DESCRIPTION

FIG. 1 is a perspective view of a micro printer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict boundaries of the micro printer that form no part of the claimed design.

1 Claim, 8 Drawing Sheets
